UNITED STATES PATENT OFFICE

134,774

DESIGN FOR A DISPLAY STAND OR LIKE ARTICLE

Leroy A. Metcalf, North Attleboro, Mass., assignor to Plainville Stock Company, Plainville, Mass., a corporation of Massachusetts

Application November 27, 1942, Serial No. 108,891

Term of patent 3½ years

To all whom it may concern:

Be it known that I, Leroy A. Metcalf, a citizen of the United States, residing in the city of North Attleboro, county of Bristol, and Commonwealth of Massachusetts, have invented a new, original, and ornamental Design for a Display Stand or like Article, of which the following is a specification, reference being had to the accompanying drawing, forming a part thereof.

Fig. 1 is a front elevational view of the display stand or like article, showing my design;

Fig. 2 is a side elevational view; and
Fig. 3 is a top plan view thereof, a portion being shown broken away for convenience of illustration.

I claim:

The ornamental design for a display stand or like article, substantially as shown and described.

LEROY A. METCALF,
